UNITED STATES PATENT OFFICE.

ERNEST C. RUSSELL, OF THE UNITED STATES REVENUE CUTTER SERVICE.

STRETCHER FOR CAP-COVERS.

1,148,718.

Specification of Letters Patent.

Patented Aug. 3, 1915.

Application filed March 10, 1914, Serial No. 823,676. Renewed January 16, 1915. Serial No. 2,721.

To all whom it may concern:

Be it known that I, ERNEST C. RUSSELL, a citizen of the United States, residing on board U. S. revenue-cutter *Tahoma*, have 5 invented certain new and useful Improvements in Stretchers for Cap-Covers, of which the following is a specification.

This invention relates particularly to frame devices upon which naval cap-covers 10 are stretched and dried after washing; and has for its object the improvement in structure and efficiency of results of such apparatus.

The invention consists in the novel construction of a drying frame and the combination and adaptation of devices for the adjustable relative movement and securing of its separable members, as will be fully described in the following specification, 20 illustrated in the accompanying drawings, and finally set forth in the appended claims.

In said drawings, Figure 1 is a top plan view of apparatus embodying my invention. 25 Fig. 2 is a longitudinal sectional view of the same shown with one of the lever-plates removed and illustrated with a cap-cover in section in operative position thereon. Fig. 3 is a perspective view of the device 30 with the cover shown thereon.

Referring to said drawings, the reference numerals 10 and 11 designate companion stretcher-members each having preferably a semi-circular configuration in plan and arranged in opposed relation so that when in closed position, they form a substantially circular frame for the reception of the cap-cover or other article it is desired to mount upon it. Each said member comprises a 35 semi-circular segmental plane bottom portion 12, an inwardly directed top flange 13, and substantially vertical side wall 15 which may be molded in any desired configuration and which is shown formed with an annular ridge 16 in the illustrated example. The adjacent edges 17 of said members are disposed diametrically to the vertical axis of the frame and when the members are closed together, are adapted to register. 45 Each of said members is provided with a vertically disposed web indicated by 18 and 18¹, respectively, rigidly secured at 19 medially of the inner surface of the walls 15 and extending axially of the frame transversely beyond the division therebetween. Said webs overlap and are slidably secured

together at their lower edges by headed pins 20 rigidly secured in one of said webs and engaged in horizontally disposed slots 21 in the companion web. Each said web is 60 formed with a relatively large horizontally elongated aperture 22. Toothed racks 23 and 24 are formed at the upper and lower horizontal edges of the apertures in said webs 18 and 18¹ respectively, while ratchet 65 teeth 25 are provided upon the web 18 for the purposes hereinafter set forth. An operating lever 26 is comprised of two plates disposed upon opposite sides of said webs and provided with a toothed pinion 27 rigidly secured between said plates and positioned in said apertures 22 and in meshed engagement with the racks 23 and 24 of the 70 respective webs, in such relation that when the upper handle end 28 of the lever is inclined in one direction, the frame members are in their contracted closed position and when said handle is pushed over into the opposite direction in the position illustrated in the views, the webs will be actuated in 75 opposite directions by the action of said pinion upon the respective racks to separate said members 10 and 11 more or less. A pawl 30 is pivoted between said handle-plates and adapted to engage the respective 80 ratchet teeth to secure said members in such 85 separated positions.

Resilient guide strips 31 are rigidly secured to one of the members, as 11, and are extended into sliding engagement with the 90 opposing member 10 and are adapted to bridge the gap separating the members and resiliently maintain the same in alinement and insure their register when they are brought into their retracted positions. 95

The manner of using the apparatus may be explained as follows: Covers indicated by C, of duck or other material, for wear over uniform-caps in the naval and military service are in common use and require frequent 100 washing. They are then drawn symmetrically and smoothly over the frame when in its retracted condition and the lever handle manipulated to separate the stretcher members 10 and 11 which stretch the fabric of the cap-cover, which is allowed to dry upon the frame. The result is that the cover dries quickly and without wrinkles in the shape it is desired to assume, without requiring ironing or other handling in order 105 to fit it for wear. After the cover is dry, the pawl 30 is released from engagement with

the ratchet teeth and the lever pushed over to cause said stretcher members 10 and 11 to approach each other, whereupon the cap-cover can be easily and quickly removed and will be without wrinkles and shaped to fit smoothly and neatly upon a cap.

While I have described my invention with some detail I do not intend to confine myself to the precise application of the invention 10 illustrated.

The invention is capable of relatively wide use and may be applied to other purposes than that shown by slight modification and change in details while remaining within the 15 spirit of the invention and scope of the claims.

Having described my invention, what I claim, is—

1. In apparatus of the class described, 20 two semicircular companion frame members having their chord surfaces in juxtaposition to afford a frame of substantially circular configuration when in their retracted positions, a web rigidly connected to each said member and directed diametrically transverse to said chord surfaces, said webs being slidably associated together in parallel planes, and each formed with an elongated registering aperture having a toothed rack, 30 respectively, upon its upper and lower edges, an operative handle-lever consisting of a pair of plates disposed upon opposite sides of said webs having a toothed pinion interposed therebetween and intermeshing with the respective racks.

2. In apparatus of the class described, two semicircular companion frame members having their chord surfaces in juxtaposition to afford a frame of substantially circular configuration when in their retracted positions, 40 a web rigidly connected to each said member and directed diametrically transverse to said chord surfaces, said webs being slidably associated together in parallel planes, and each formed with an elongated registering aperture having a toothed rack, 45 respectively, upon its upper and lower edges, one of said webs being provided with ratchet teeth, an operative handle-lever consisting 50 of a pair of plates disposed upon opposite sides of said webs having a toothed pinion interposed therebetween and intermeshing with the respective racks, and a pawl mounted in said lever adapted to engage said

ratchet teeth and secure said frames in separable adjusted positions.

3. In apparatus of the class described, two semicircular companion frame members having their chord surfaces in juxtaposition to afford a frame of substantially circular configuration when in their retracted positions, a web rigidly connected to each said member and directed diametrically transverse to said chord surfaces, said webs being slidably associated together in parallel planes, and each formed with an elongated registering aperture having a toothed rack, respectively, upon its upper and lower edges, an operative handle-lever consisting of a pair of plates disposed upon opposite sides of said webs having a toothed pinion interposed therebetween and intermeshing with the respective racks, and means to secure said frame-members in adjusted extended positions.

4. In apparatus of the class described, two semicircular companion frame-members connected together to form a substantially circular frame in retracted position, said connections consisting of diametrically disposed webs respectively secured at one end to the walls of the frame members, an oppositely directed toothed rack in the respective webs, an operating handle lever provided with a toothed pinion in mesh between said racks and adapted to reciprocate said members in opposite directions at each partial rotation.

5. In apparatus of the class described, two semi-circular companion frame-members connected together to form a substantially circular frame in retracted position, 90 said connections consisting of diametrically disposed webs respectively secured at one end to the walls of the frame-members, an oppositely directed toothed rack in the respective webs, 95 an operating lever provided with a toothed pinion in mesh between said racks and adapted to reciprocate said members in opposite directions at each partial rotation, and means to secure said frame-members in adjusted extended positions.

Signed at Seattle, Wash., this 18th day of February, 1914.

ERNEST C. RUSSELL.
